UNITED STATES PATENT OFFICE.

BERRY V. STOLL, OF LOUISVILLE, KENTUCKY.

ROTARY TOOTHBRUSH.

Application filed August 6, 1926. Serial No. 127,653.

This invention relates to tooth brushes and has as its general object to provide a tooth brush which, by reason of its construction and mode of operation, will more effectually brush and cleanse the teeth than the ordinary brush. It is a well known fact that while dentists urge their patients to not only employ the ordinary tooth brush by brushing backwardly and forwardly across the teeth but also with an up and down motion, the average person will neglect to use the brush in the latter manner, with the result that food accumulations are not completely removed from between the teeth and decay shortly ensues. Furthermore, in the use of the ordinary tooth brush the incisor and canine teeth are subject to a more thorough brushing than the molars, where the brush is merely given a back and forth motion. Therefore, the invention contemplates the provision of a tooth brush so constructed and adapted to be so operated that the teeth will be brushed in the proper manner so as to effectually remove all food accumulations from between the teeth and from the surfaces thereof and permit of uniform treatment of all of the teeth without subjecting the incisor and canine teeth to excessive brushing which tends to wear away the enamel and render the teeth sensitive.

Another object of the invention is to provide a tooth brush which may be more conveniently manipulated than the ordinary brush and with less energy and which will insure of a brushing of the teeth in a vertical direction rather than crosswise, thus effecting a more thorough cleaning of the teeth and minimum wearing away of the enamel.

In the accompanying drawings:

Figure 1 is a perspective view of the tooth brush embodying the invention, the view illustrating the manner in which the brush is to be held and operated.

Figure 2 is a detail vertical sectional view taken substantially on the line 2—2 of Figure 1, looking in the direction indicated by the arrows.

Figure 3 is a horizontal sectional view taken substantially on the line 3—3 of Figure 1, looking in the direction indicated by the arrows.

Figure 4 is a perspective view of the brush proper separated from the operating mechanism.

The device comprises a handle including a fixed section indicated in general by the

numeral 1 and a movable section or member indicated in general by the numeral 2. The member 1, as also the member 2, is formed of sheet metal and comprises a flat-sided substantially oblong rectangular body 3 provided at one end with an opening 4 of a contour to accommodate the first joint of the thumb of the user. The body 3 is provided with longitudinal flanges 5 at its opposite edges and these flanges are spaced from one face of the body and accommodate the lateral edges of the body 6 of the member 2 of the handle so that the member 2 is 60 slideable upon and with relation to the said member 1, the member 2 being provided at its outer end with an opening 7 of a size and contour to accommodate the first joint of the forefinger of the hand of the user. A slot 8 is formed transversely in the body 3 of the member 1, and a substantially semi-cylindrical barrel 9 is secured to or integrally united 65 at its open side with the said body 3 and covers the said slot. For a purpose to be presently explained, the barrel 9 is provided at one end with an extension 10 which is uniformly concave in cross section throughout its length and which constitutes a guard 70 for the brush proper.

Bearing sleeves 11 and 12 are mounted 75 upon the body 3 at opposite sides of the slot 8 therein and within the opposite ends of the housing 9, and a shaft 13 is journaled in the said sleeves and has fixed upon it, between the relatively adjacent ends of the 80 sleeves, a pinion 14 which engages at its peripheral portion through the slot 8. As the pinion is fixed upon the said shaft or spindle, longitudinal displacement of the spindle in the bearing sleeves is prevented. At its 85 end which is presented toward the extension 10 of the barrel 9, the spindle 13 is provided with a cylindrical extension 15 concentrically housed within the inner end of the said extension 10 and provided with a rectangular socket 16 to accommodate the shank 17 of the brush proper. The brush comprises a cylindrical head 18 at one end of which the said shank is located, and this head is provided with bristles 19 which radiate from all parts of the circumference thereof so that the brush body is of cylindrical contour. The body is of a diameter to adapt one side thereof to be concentrically positioned within the extension 10 and, 100 therefore, the extension constitutes a guard 105 to prevent the bristles coming in contact 110

with the cheeks when the brush is inserted into the mouth, particularly in brushing the molars, it being understood that rotary motion of the spindle 13 will result in corresponding movement of the brush as a whole so as to effect a thorough cleansing of the teeth.

Rotary motion of the spindle 13 is effected through reciprocation of the member 2 with respect to the member 1 and in order that this may be accomplished, the body 6 of the member 2 is formed with a longitudinal slot 20 the side walls of which register with the side walls of the slot 8, and a rack bar 21 is united at its ends to the outer face of the said body 6 and extends longitudinally of the said slot 20 and has its rack teeth 22 projecting into the said slot 20 and engaged by the teeth of the pinion 14.

20 In using the brush, the forefinger and thumb are inserted into the openings 7 and 4 respectively, the stem or shank 17 of the brush, which shank is of polygonal cross section, having been fitted into the socket 16, and the member 2 is then reciprocated with respect to the member 1, the brush 19 being held against the teeth and moved back and forth while being alternately rotated in opposite directions through the reciprocation 30 of the rack 21 past the pinion 14. It will be evident, therefore, that due to the character of the brush head and the motion imparted thereto, the bristles will work between the teeth and effectually remove all food accumulations. Consequently, the brush is adapted to act upon the teeth in the most effective manner. It will be understood that the extension 10 constitutes a guard to prevent the head 15 of the spindle 13 and likewise the bristles 19 of the brush coming in contact with the lips or cheeks when the brush is inserted into the mouth and while the brush head is being rotated. Likewise, this guard serves to prevent the dentifrice 40 which is applied to the brush head being thrown off in a forward direction through centrifugal force.

It will be evident from the foregoing description that the brush head may be readily removed or separated from the supporting and actuating means therefor and another head substituted therefor, and, therefore, brush heads having bristles of different degrees of stiffness may be substituted one for another and when one brush head has become so worn as to be unfit for use it may be discarded and another head readily substituted.

60 While the brush is designed primarily as a tooth brush, it will be evident that it may be made in larger sizes and put to other uses.

It will be evident from the foregoing description of the invention that the device, 65 with the exception of the brush proper, can

be, in its entirety, stamped from sheet metal, thus enabling the same to be produced at a low cost.

Having thus described the invention, what I claim is:

70 1. A brush comprising a handle having companion sections formed of flat sheet metal and having their inner end portions overlapped and their outer ends provided with finger-engaging portions, means slidably connecting said sections, one section being formed with a longitudinally extending slot and the other with an opening communicating with the slot, a rack carried by the first section and having its teeth extending across 75 said slot, a shaft rotatably connected with the second section and extending across the opening, a pinion carried by said shaft and projecting through the opening and engaged with said rack whereby rotary motion will be imparted to said shaft when the handle sections are moved, a brush head carried by said shaft, and a guard for said pinion carried by the second handle section and having a portion projecting from the handle and forming a shield extending longitudinally 80 of and partially about the brush head.

85 2. A brush comprising a handle having companion sections slidable longitudinally of each other and having overlapped inner end portions and their outer end portions adapted for engagement with the fingers of an operator, one section having its inner end portion formed with an opening and the other section having a slot communicating 90 with the opening, a bearing carried by the first section, a shaft journaled in said bearing and extending across the opening and projecting from one side of the section, a pinion carried by said shaft and projecting through the opening and slot, a rack carried by the second section and having teeth 95 extending across its slot and engaging said pinion to impart rotary motion to the pinion and shaft when the sections are slid longitudinally of each other, and a brush head carried by said shaft.

100 3. A brush comprising a handle having companion sections slidable longitudinally of each other and having overlapped inner end portions and their outer end portions adapted for engagement with the fingers of an operator, one section having its inner end portion formed with an opening and the other section having a longitudinally extending slot communicating with the opening, bearings carried by the first section at 105 opposite sides of the opening, a shaft journaled in said bearings and extending across the opening and projecting from one side of the section, a pinion carried by said shaft and projecting through the opening and slot, a rack extending longitudinally of the second section in covering relation to its slot 110 and engaging said pinion to impart rotary 115 motion to the pinion and shaft.

motion to the pinion and shaft when the sections are slid longitudinally of each other, a brush head carried by the outer end portion of said shaft, and a semi-cylindrical barrel extending transversely upon the first handle section in covering relation to the bearings and pinion and having a transversely concaved extension projecting from the handle section and disposed longitudinally of and partially about the brush head and extended portion of said shaft.

4. A brush comprising a handle having companion sections formed of flat strips having their inner end portions overlapped and their outer end portions formed with finger-receiving openings, flanges carried by one handle section along its sides and provided with inwardly extending lips overlapping the other handle section to slidably connect the sections, one handle section being formed with a longitudinally extending slot and the other with an opening com-

municating with the slot, a plate covering said slot and having its inner face formed with rack teeth, bearings at opposite sides 25 of said opening, a shaft journaled in said bearings and projecting transversely from the handle and provided with a head having a socket leading from its outer end, a pinion upon said shaft between said bearings and 30 projecting through the opening and slot and meshing with said rack teeth, a brush head having a stem removably fitted into the socket of said shaft head, and a semi-cylindrical barrel rigid upon the handle section 35 formed with the opening and disposed transversely thereof in covering relation to the bearings and pinion and having a transversely concaved extension extending longitudinally of and partially about the shaft 40 head and brush head.

In testimony whereof I affix my signature.

BERRY V. STOLL. [L. s.]
